UNITED STATES PATENT OFFICE.

JESSE H. SROFE, OF KOKOMO, INDIANA.

DESIGN FOR A WIRE FENCE.

SPECIFICATION forming part of Design No. 31,474, dated August 29, 1899.

Application filed August 7, 1899. Serial No. 726,478. Term of patent 7 years.

To all whom it may concern:

Be it known that I, JESSE H. SROFE, a citizen of the United States, residing at Kokomo, in the county of Howard and State of Indiana, have invented and produced a certain new Design for Wire Fences, of which the following is a specification.

In the drawing I have shown a side elevation of a wire fence presenting my design.

As shown in the drawing, the leading or material feature of my design consists of the fence having the several horizontal or cross strands A, B, C, and D and the pickets E and F. The pickets E have the curved tops e, which stand side by side above the strand A without overlapping, as shown, and have the parallel portions e' between the strands A and B, the inclined portions e'' between the strands B and C, converging toward each other and contacting at strand C, and the inclined but diverging portions e''' between the strands C and D, and the lower end portions which converge below the lower strand D. The pickets F have the diamond-shaped tops f, which stand above the top strand A, inside of the space between the curved top e of the picket E and midway between the ends of the curve e. Continuing from the said dia-

mond are the parallel portions f' between the strands A and B, the inclined portions f'' between the strands B and C, diverging and crossing the inclined portions e'' of the other picket, and the inclined but converging portions f''' between the strands C and D, and the lower end portions which diverge below the lower strand D, as shown.

The pickets and the cross-strands A, B, C, and D present the appearance of twisted wire, giving the panel and pickets the appearance of a fabric. The crossings of the inclined members of the pickets below the horizontal strand B form a series of diamonds and half-diamonds, as shown.

Having described my invention, what I claim as new, and wish to secure by Letters Patent, is—

The design for a wire fence as herein shown and described.

In witness whereof I have hereunto set my hand and seal, at Indianapolis, Indiana, this 24th day of July, A. D. 1899.

JESSE H. SROFE. [L. S.]
